UNITED STATES PATENT OFFICE.

FRED F. EVERETT, OF WEEPING WATER, NEBRASKA.

END-GATE FOR WAGONS.

SPECIFICATION forming part of Letters Patent No. 321,891, dated July 7, 1885.

Application filed April 23, 1885. (No model.)

To all whom it may concern:

Be it known that I, FRED F. EVERETT, a citizen of the United States of America, residing at Weeping Water, in the county of Cass and 5 State of Nebraska, have invented certain new and useful Improvements in End-Gates for Wagons; and I do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification. 15

My invention relates to certain new and useful improvements in end-gates for wagons; and it consists in the construction and combination of the parts, as will be hereinafter 20 fully set forth, and specifically pointed out in the claims.

In the accompanying drawings, which illustrate my invention, Figure 1 is a perspective view showing my improved end-gate in a 25 vertical position. Fig. 2 is a perspective view of the same, showing the gate in an inclined position. Fig. 3 is a view showing the gate detached from the wagon-body.

A represents a wagon-body, the ends of the 30 side-boards being provided with vertical cleats or battens *a a*, between which the ordinary end-gate is usually placed. To the outside of the side-boards, near their upper corners, are attached chains *B B*, one of said 35 chains being provided with a loop over which is placed a sliding ring, said loop carrying a cam-bar which is adapted to be inserted in the opposite link of the other chain. This finger or cam-bar is held in position by the 40 sliding ring attached to the loop, which is slid over the same.

The end-gate proper, which is indicated by the letter *C*, consists of an end or bottom piece, *D*, to the sides of which are attached 45 inclined side pieces, *d d*. The end or bottom piece is re-enforced by cross-battens *e e'*, the upper batten having attached at its ends straps *f*, the ends of which project beyond the same, and are formed into hooks *f'*. The 50 lower edge of the end-gate proper has se-

curely attached to the corners thereof corner-irons *g g*, from which project pivot-pins *g'*, which engage with the recess formed between the vertical battens *a a*, attached to the inner ends of the side-boards. The lower 55 transverse batten, *e'*, which is attached to the lower side of the bottom piece, *D*, is of such a distance from the lower edge thereof that when the end-gate is placed in a horizontal position this batten will abut against the 60 outer edge of the bottom board of the wagon-body and hold the end-gate in a horizontal position.

When it is desired to use the end-gate in an inclined position, as shown in Fig. 2, the 65 last links of the chains *B B* are placed over the hooks *f'*, which will serve to hold the end-gate in the position shown in Fig. 2 of the accompanying drawings.

When it is desired to hold the end-gate in 70 a vertical position, the ends of the chains are brought over the rear end of the wagon-body, so that the hooks *f'* will be above the inner links of the chains, and said chains are then brought tightly together and secured. By this 75 construction the side-boards of the wagon-body are held together and the end-gate is prevented from being raised vertically.

The end-gate hereinbefore described, besides being simple and cheap in construction, 80 and adapted to be placed in the position hereinbefore described, will serve as a scoop or shoveling board for unloading the wagon.

I claim—

1. The improved end-gate for wagons herein described, consisting of a bottom board having side pieces attached thereto, and transverse battens *e e'*, the lower corner of said end-gate having projecting pins *g'*, the upper batten having hooks *f'*, in combination with 90 a wagon-body having vertical battens *a a*, and independent chains *B B*, each adapted to engage one of the hooks *f'*, to support the end-gate in an inclined position, so as to engage 95 each other to maintain said gate in a vertical position, substantially as shown, and for the purpose set forth.

2. In combination with a wagon-body having vertical strips *a a*, attached to the inner sides of the side-board, and chains attached to 100

the upper corner thereof, said chains being provided with connecting means, an end-gate having bottom boards and side pieces, the lower corners of said end-gate having attached thereto angle-plates with projecting pins g' , the transverse batten, e , with hooks f' , and a lower transverse batten e' , the parts being organized so that the gate may be held in either a

vertical or inclined position by means of said chains, substantially as set forth.

In testimony whereof I affix my signature in presence of two witnesses.

FRED F. EVERETT.
